Hillsdale, Mich., assignors to Allied Products
Corporation, Detroit, Mich., a corporation of
Michigan

Application July 17, 1943, Serial No. 495,114

10 Claims. (Cl. 125—11)

This invention relates to a wheel dressing tool holder.

It is the object of the invention to provide a relatively simple, but effective, tool holder for dressing a grinding wheel or other wheel with a tool that turns sequentially on more than one radius. It is sometimes desirable to provide a groove on a grinding wheel or other wheel formed in cross-section on arcs which have different radii.

It is the object of the present invention to provide for this purpose a simple tool holder that may be secured in a standard grinding wheel profiling attachment.

In the drawing:

Fig. 1 is a fragmentary elevational view partly in section showing a grinding wheel and a profiling attachment with our improved tool holder in place.

Fig. 2 is an end elevation of our improved tool holder.

Fig. 3 is a cross-section of the same showing the removable operating crank in place.

Fig. 4 is a perspective showing the tool holder and the operating crank in the initial position.

Fig. 4a is a companion diagrammatic view showing the tool in the position with respect to the work which it takes when the tool holder parts are in the position shown in Fig. 4.

Fig. 5 is a perspective showing the tool holder after the crank has turned the inner supporting shaft through 90°.

Fig. 5a is a companion diagrammatic view showing the position of the tool with respect to the work.

Fig. 6 is a perspective view showing the tool holder and crank after the crank has been turned through 180°.

Fig. 6a shows the tool with respect to the work when the parts are as shown in Fig. 6.

Fig. 7 is a detailed perspective showing the operating crank pressed in to return the rotary parts of the holder to their initial position.

The grinding wheel is designated 1. 2 is the casing enclosing the grinding wheel. 3 designates a grinding wheel profiling attachment which is of standard construction and available on the market. This is provided with a head or chuck which ordinarily carries a nib or dop into the end of which is soldered or otherwise fastened a diamond for dressing the periphery of the grinding wheel in the usual way.

We have designed a dressing tool holder which has a shank 5 that may be secured in the chuck or sleeve in the usual manner that a nib is secured

in place. This shank carries a body into which one or more rotating tool holders may be supported. We have shown only one here in the drawing. A rotating shaft 7 is supported in a rotatable bushing 8. The bushing has an enlarged head 9 and a coiled expansion spring 10 bearing against the pin 11 which is driven into shaft 7 puts a load on both washers 14 and 15 and thereby establishing frictional resistance to the turning of either the bushing or the shaft 7. This tends to keep both the shaft and the bushing in any position to which either is turned.

Referring to Figs. 4a, 5a, and 6a, it will be seen that a diamond 40 is carried in the nib or dop 16. Fig. 4a shows the position of the diamond with respect to the periphery of the grinding wheel 1. It will be noted that the bottom of the groove on the right hand side is formed on an arc whose center is at 17. In Fig. 5a the tool is shown on the very bottom of the groove but still the nib turns on the center 17, but at this point the tool is about to shift the center on which it turns. In Fig. 6a it is shown turning on the center 18 which affords a larger radius.

In Fig. 4 the two rotating tool supports (the bushing 8 and the shaft 7) are shown in the position they assume with the tool in the position shown in Fig. 4a. A crank 19 is provided with a sleeve or socket 20 which has two slots 21 and 22. Note that in Fig. 4 slot 22 embraces pin 23 on the underside of shaft 7. This is preparatory to the initial turning of the diamond. In Fig. 5 the crank 19 has been turned through 90° and so has shaft 7 by reason of the keying of the shaft to the socket of the crank by means of slot 22 and pin 23. At this point pin 24 is the shaft is about to pick up stud 25 in the head 9 of the bushing. When this pick-up is effected the shaft and the bushing turn together. Consequently, the radius on which the nib or diamond dop turns shifts from center 17 to center 18, which is the center on which the bushing turns. The shaft is eccentrically supported in the bushing.

Referring to Fig. 6, it will be seen that the crank is now turned through 180°. The bushing is turned through 90° and the key lug 26 has turned from a horizontal position in Figs. 4 and 5 to a vertical position. Pin 27 in the periphery of the bushing head has now encountered stud 28 in the body of the tool holder and stopped further counter-clockwise turning of the two rotary tool supports. The diamond (Fig. 6) has been turned to the position where it has finished the work on the left hand side of the groove and has fin-

ished turning through an arc of 90° on the larger radius whose center is at 18.

To return the tool, the crank is now pushed in further, as shown in Fig. 7, and the slot 22 now straddles the key lug 26 as well as pin 23. The crank may now be turned clockwise and both the shaft and the bushing will turn 90° therewith. At the end of 90° pin 27 encounters stud 29 protruding from the body of the tool holder. This arrests further turning of the crank until the inward pressure on the crank handle is released and spring 30 causes the crank to shift outwardly causing slot 22 to clear the key lug 26. The turning of the crank in a clockwise direction may now be resumed and continued through 90° which will bring the nib 16 back to the position shown in Fig. 4a.

It will be evident that the dressing tool may be swung back and forth oscillating the crank through 180°. The tool holder will automatically shift from turning on one radius to turning on the larger radius, as the diamond reaches the bottom of the groove in the counter-clockwise swing of the crank. Then the tool is pressed in and as the crank swings in a clockwise direction the turning will be arrested at the bottom of the groove. The pressure can then be released on the crank and the tool will shift to turn on the smaller radius.

What we claim is:

1. In a tool holder for the purpose described, the combination of a body, two rotatable tool supports supported to turn therein, one contained within the other, and rotatable on eccentric axes, the inner rotatable tool support arranged to carry the tool, the said two rotatable tool supports having interengageable members and arranged first for independent rotation of the inner support and then to be automatically coupled by the interengagement of said members for continued rotation of the two supports together in the same direction, thereby causing the tool to rotate first on one radius and then on another radius as the tool supports are turned in one and the same direction.

2. In a tool holder for the purpose described, the combination of a body, two rotatable tool supports supported to turn therein, one contained within the other, and rotatable on eccentric axes, the inner rotatable tool support arranged to carry the tool, the said two rotatable tool supports having interengageable members and arranged first for the rotation of the inner tool support independently and then the inner tool support automatically picking up the outer rotating tool support by interengagement of said members to cause the two tool supports to rotate together in the same direction on the larger radius, a stop and hand actuated means for rotating the inner tool support and manipulatable to tie the two supports together for part of the return inactive movement of the tool until the stop is reached and then release the outer support for the rest of the return inactive movement of the tool in the same direction.

3. In a tool holder for the purpose described, the combination of a body, two rotatable tool supports supported to turn therein, one contained within the other, and rotatable on eccentric axes, the inner rotatable tool support arranged to carry the tool, the said two rotatable tool supports arranged first for the rotation of the inner tool support independently and then the inner tool support picking up the outer rotating tool support to cause the two tool supports to rotate together on the larger radius, the said inner rotating tool support

gather on the larger radius, the said inner rotating tool support being provided with a pin and the outer rotating tool support being provided with a stud arranged to be picked up by the pin after a given independent rotation of the inner tool support.

4. In a tool holder for the purpose described, the combination of a body, two rotatable tool supports supported to turn therein, one contained within the other, and rotatable on eccentric axes, the inner rotatable tool support arranged to carry the tool, the said two rotatable tool supports arranged first for the rotation of the inner tool support independently and then the inner tool support picking up the outer rotating tool support to cause the two tool supports to rotate together on the larger radius, the said inner rotating tool support being provided with a pin and the outer rotating tool support being provided with a stud arranged to be picked up by the pin after a given independent rotation of the inner tool support, and means for stopping the coupled rotation of the two supports after a given angular movement of the same.

5. In a tool holder for the purpose described, the combination of a body, two rotatable tool supports supported to turn therein, one contained within the other, and rotatable on eccentric axes, the inner rotatable tool support arranged to carry the tool, the said two rotatable tool supports arranged first for the rotation of the inner tool support independently and then the inner tool support picking up the outer rotating tool support to cause the two tool supports to rotate together on the larger radius, the said inner rotating tool support being provided with a pin and the outer rotating tool support being provided with a stud arranged to be picked up by the pin after a given independent rotation of the inner tool support, and means for stopping the coupled rotation of the two supports after a given angular movement of the same.

6. In a tool holder for the purpose described, the combination of a body, two rotatable supports supported to turn therein, one contained within the other, and rotatable on eccentric axes, the inner rotatable tool support arranged to carry the tool, the said two rotatable tool supports arranged first for rotation of the inner tool support independently and then the inner tool support picking up the outer rotating tool support to cause the two tool supports to rotate together on the larger radius, the said inner rotating tool support being provided with a pin and the outer rotating tool support being provided with a stud arranged to be picked up by the pin after a given independent rotation of the inner tool support, and means for placing a load upon the two rotatable members to provide frictional resistance to their turning.

7. In a tool holder for the purpose described, the combination of a body, two rotatable supports supported to turn therein, one contained within the other, and rotatable on eccentric axes, the inner rotatable tool support arranged to carry the tool, the said two rotatable tool supports arranged first for the rotation of the inner tool support independently and then the inner tool support picking up the outer rotating tool support to cause the two tool supports to rotate together on the larger radius, the said inner rotating tool support being provided with a pin and the outer rotating

tool support being provided with a stud arranged to be picked up by the pin after a given independent rotation of the inner tool support, the said inner rotary member provided with an exposed portion carrying a projecting key pin and the said outer rotary member carrying a key lug whereby a crank with a slotted socket may be engaged over the projecting portion of the inner rotary member to pick up first the key pin and then rotate the inner support a pre-determined distance and then rotate both rotary supports a further angular distance, the key pin registering with the key lug whereupon the crank socket may be pushed in further to key the crank to the outer rotary member by the slot straddling the key lug to couple the two together for return rotation.

8. In a tool holder for the purpose described, the combination of two rotatable tool supports, one contained within the other, and rotatable on eccentric axes, the inner rotatable tool support arranged to carry the tool, the said supports arranged first for the rotation of the inner support independently and then the inner support picking up the outer rotating support to cause the two supports to rotate together on the larger radius, the said inner rotating support being provided with a pin and the outer rotating support being provided with a stud arranged to be picked up by the pin after a given independent rotation of the inner support, the said inner rotary support provided with an exposed portion carrying a projecting key pin and the said outer rotary support carrying a key lug whereby a crank with a slotted socket may be engaged over the projecting portion of the inner rotary support and turn the inner rotary support through its independent movement and also through its coupled movement with the outer rotary support in one direction of the turning, then the crank socket may be pushed further in on the exposed portion to straddle the key lug to return both rotary supports, and means for stopping the outer support upon a pre-determined angular return movement permitting partially withdrawing the crank socket and continuing the return movement of the inner rotary support.

9. In a tool holder for the purpose described, the combination of two rotatable tool supports, one contained within the other, and rotatable on eccentric axes, the inner rotatable tool support arranged to carry the tool, the said supports ar-

ranged first for the rotation of the inner support independently and then the inner support picking up the outer rotating support to cause the two supports to rotate together on the larger radius, the said inner rotating support being provided with a pin and the outer rotating support being provided with a stud arranged to be picked up by the pin after a given independent rotation of the inner support, the said inner rotary support provided with an exposed portion carrying a projecting key pin and the said outer rotary support carrying a key lug, a crank with a spring therein and a slotted socket which may be engaged over the projecting portion of the inner rotary support and turn the inner rotary support through its independent movement and also through its coupled movement with the outer rotary support in one direction of the turning, then the crank socket may be pushed further in on the exposed portion to straddle the key lug to return both rotary supports, and means for stopping the outer support upon a pre-determined angular return movement permitting the spring in the crank socket partially withdrawing the crank socket and continuing the independent return movement of the inner rotary support.

10. In a tool holder for the purpose described, the combination of a body, two rotatable tool supports supported to turn therein, one contained within the other, and rotatable on eccentric axes, the inner rotatable tool support arranged to carry the tool, the said two rotatable tool supports having interengageable members and arranged first for the rotation of the inner tool support independently and then the inner tool support automatically picking up the outer rotating tool support by interengagement of said members to cause the two tool supports to rotate together in the same direction on the larger radius, a stop and hand actuated means for rotating the inner tool support and manipulatable to tie the two tool supports together for part of the return movement of the tool until the stop is reached and then release the outer support for the rest of the return movement of the tool, the said means comprising a crank pressed in to tie the two supports together and released from said pressed-in position when the stop is reached to release the outer support for the remainder of the return movement.
